UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed October 21, 1921, Serial No. 509,242. Renewed October 12, 1926.

My invention relates to electric switches, and particularly to the construction of the switch mechanism, the object of my invention being to provide a mechanism of the 5 tumbler type having certain improved features of construction and operation herein-after pointed out or illustrated in the accompanying drawings, in which—

Fig. 1 is a vertical section through a flush 10 switch in which my invention is embodied in one form;

Fig. 2 is a section on the line 2—2, Fig. 1;

Fig. 3 is a perspective of the switch bar rocker;

Fig. 4 is a perspective of the operating lever; and

Fig. 5 is a perspective of the switch frame.

The invention is here shown embodied in a flush switch comprising a cup-shaped insulating body 6, the open face of which is spanned by the supporting frame 7. The latter is centrally interrupted, but its opposite ends are joined by the side members 8 and 9, which are here shown integral with 20 the supporting ends. Wire terminals 10 are arranged on depressed ledges 11 at the four corners of the switch chamber and have switch contact lugs 12 and 13 for cooperation with the two switch blades 14 and 15, 25 the switch in the form here shown being of the double-pole type.

The switch mechanism is of the toggle type and comprises a switch bar yoke 16 rocking on the open bearings 17 and carrying the switch bars 14 and 15. A tongue 18 is formed in the yoke bridge for attachment to one end 19 of the actuating pull spring 20. The other end of the spring is engaged at 21 to the operating lever 22 by which it 30 is swung from one side to the other of the axis of oscillation of the switch yoke 16. As already indicated in Fig. 2, the switch bar yoke 16 straddles the frame members 8 and 9, while the operating lever 22 lies between the latter.

This operating lever is a flat sheet metal bar provided at its outer end with a suitable finger piece or handle 30, preferably of insulation. This lever is pivoted near its inner end to the frame members 8, 9, and at 35 that end is slotted in the direction of its length to form an open forked end in which can work the pull spring 20, this spring being connected to the lever at 21 at the head

of the fork, while at the other end the spring 55 is connected to the yoke at 18. The legs of this fork and the legs of the switch bar yoke 16 overlap each other, and since both these devices have their pivots near their outer ends, a relatively long spring 20 can be employed with good effect, and with a long 60 movement of the switch contacts.

In order that the lever 22 may be introduced to operating position, the frame members 8 and 9 are slotted at 23 to one 65 side of hook bearings 24, in which the shoulders 25 of the lever 22 pivot. At the head of the slots 23, lugs 26 are outwardly offset to form bearing studs against which the notch bearings 17 of the switch yoke are 70 pressed by the tension of the spring 20 when the parts are assembled. The arms of the yoke 16 are apertured at 27 to receive, with lost motion, the lugs 28 on the switch lever, and by which a positive movement is imparted to the yoke to initiate the throw of 75 the switch bars.

The mechanism is easily assembled with the frame. After the lever 22 has been placed between the arms of the switch yoke 80 16 with the lugs 28 entering the recesses 27, and with the spring 19 engaged at 18 and 21, the mechanism is mounted on the frame by passing the lever 22 up between the side frame members 8 and 9 until the arms of 85 the switch yoke, which straddle the frame, engage the bearing studs 26 in the notches 17. If the lever 22 is now pulled against the tension of the spring 20, the bearing shoulders 25 of the lever may be lifted and 90 swung over the ends of the hooks which form the bearings 24 against which the shoulders 25 are then automatically depressed by the pull of the spring. The spring 20 now maintains the notches 17 of 95 the switch yoke against the bearing studs 26 and the shoulders 25 of the lever 22 in the bearing notches 24. The yoke 27, with the switch mechanism assembled thereon, is now ready for assembly on the switch body 6. 100

The operation of the switch is readily understood. In Fig. 1 the switch is shown in circuit-closing position with the switch bars 14 and 15 in engagement with the switch contacts 12 and 13. To shift the switch to 105 open-circuit position the lever 22 which passes through the open area 29 in the switch frame, is swung on the bearings 24 by means

of the thumb piece 30 at the free end of the lever. As it swings across its arc, its lugs 28 engage the sides of the apertures 27 in the arms of the switch yoke 16 substantially simultaneously with the passage of the end 21 of the switch spring 20 across the axis of oscillation 17 of the yoke, thus positively shifting the switch bars in a direction to break engagement with the switch contacts 12 and 13. As the switch lever completes its arc of travel, the pull of the spring 20 causes the switch yoke 16 to swing with snap action to open-circuit position, that is to say, from its stop position against the legs 31 of the switch frame to the stop position against the legs 32. To again close the circuit the switch lever is swung in opposite direction, thus repeating the movement, but in reverse direction, and again shifting the switch bars to circuit-closing position with snap action. The slot 33 in the switch lever accommodates the switch spring as it swings from one side to the other thereof on the operation of the switch.

It will be noted that the point of engagement between the lugs 28 on the switch lever and the sides of the apertures 27 in the arms of the yoke is substantially aligned with the axes of oscillation 17 and 24 of the switch bar and switch lever respectively, but the shape of the apertures 27 is such that the engagement of the lugs does not occur until the end 21 of the spring 20 reaches or slightly passes the axis 17, thus insuring a positive separation of the contacts and switch bar only when the spring is under tension and in position to accelerate the positive separation of these parts and effect a quick break by the switch bar movement thus initiated.

The construction is extremely simple and economical since the frame 7, switch bar yoke 16, and lever 22 may all be struck from sheet metal and bent to shape, while the assembly of the parts is readily accomplished without the use of independent pivot pins or the like. The angular opening 23 through which the switch lever 22 is introduced into its bearings 24 permits the bearing hooks to be so shaped that there is no danger of the shoulders 25 jumping out of their bearing notches 24. Moreover, even should an attempt be made to disarrange the switch by pulling the lever 22 outward to unseat the shoulders 25 from the bearing notches 24, the effort is not likely to be successful since the several parts must be in exact predetermined position to permit the shoulders 25 to ride over the noses of the bearing hooks.

The bay 34 in the margin of the apertures 27 in the yoke arms accommodates the lugs 28 when the switch yoke 16 and lever 22 are assembled and insures the maintenance of these parts in proper relation as an assembly unit under the pull of spring 20, until

they are engaged with the frame member 7.

Various modifications in detail of construction will readily occur to those skilled in the art, without departing from what I claim as my invention.

I claim—

1. In an electric switch, an insulating body, a supporting yoke secured thereto and having webs offset therefrom, to form the spaced side members of the frame, the yoke being apertured between the side members to accommodate an operating lever, a switch bar rocker straddling the side members of the frame, a forked operating lever arranged between the side members of the frame and extending through the aperture in the yoke for manual operation, cooperating open bearing members for pivoting the rocker and lever respectively on different axes on the frame, and a pull spring operatively connecting said rocker and lever, and connected to the lever at a point shiftable across the axis of oscillation of the rocker on the operation of the switch lever.

2. In an electric switch, a switch frame having an apertured side plate, a switch bar pivotally mounted at one side of said plate and being apertured in register with the aperture in the frame plate, a switch operating lever pivoted on an independent axis and arranged on the opposite side of the frame plate and having a lug passing through the aperture in the frame plate and engaged with lost motion in the aperture in the switch bar, a switch spring operatively engaged between said switch bar and lever and connected to the lever at a point shiftable across the axis of oscillation of the switch bar on the operation of the switch lever, said lug on the lever and aperture in the switch bar being of such dimensions and so located that the lug engages one or the other side of the aperture approximately simultaneously with the passage of the end of the spring attached to the switch lever across the axis of oscillation of the switch bar to impart a positive impulse to the latter in the direction of its throw.

3. In an electric switch, a switch lever comprising a substantially flat sheet metal bar slotted at one end in the direction of its length to form a forked end, bearing shoulders at the outer margins of the ends of the legs of the fork, a switch-operating spring pivoted to the lever at the head of the fork and working between the legs thereof, in combination with a switch bar rocker to which the opposite end of the spring is secured.

4. In an electric switch, a switch lever comprising a substantially flat sheet metal bar slotted at one end in the direction of its length to form a forked end, bearings at the outer edges of the free ends of the legs of the fork, outwardly extending lugs spaced

- from the ends of the fork, a switch operating spring pivoted to the lever at the head of the fork and working between the legs thereof, in combination with a switch bar rocker to which the opposite end of the spring is secured, said rocker being apertured to accommodate the outwardly extending lugs on the lever, said lugs working freely in the apertures but adapted to engage the boundaries thereof to initiate the throw of the rocker in opposite directions.
5. In an electric switch, a switch lever comprising a substantially flat sheet metal bar slotted at one end in the direction of its length to form a forked end, bearings at the outer edges of the free ends of the legs of the fork, outwardly extending lugs spaced from the ends of the fork, a switch operating spring pivoted to the lever at the head of the fork and working between the legs thereof, in combination with a switch bar rocker to which the opposite end of the spring is secured said rocker being apertured to accommodate the outwardly extending lugs on the lever, said lugs working freely in the apertures but adapted to engage the boundaries thereof to initiate the throw of the rocker in opposite directions, the aperture in the rocker being shaped to afford a bay opening thereto, said spring being sufficiently stressed on the assembly of the switch lever with the rocker to maintain the parts assembled with the lever lugs engaged in said bay.
6. In an electric switch, a switch frame comprising spaced supporting ends united by side frame members extending at right angles thereto and slotted at their free ends, spaced bearings on said side frame members, in combination with a self-contained and self-sustained assembly unit comprising a switch bar rocker, an operating lever and a switch spring engaged between the same, said unit being adapted for direct self-contained assembly on the frame and having bearing elements adapted for engagement with the bearings on the switch frame and self-maintenance thereon under the tension of the spring.
7. In an electric switch, a switch frame comprising spaced end supporting lugs, and intermediate connecting members extending at right angles thereto, said side members having open bearing hooks at their free ends and outwardly extending bearing studs intermediate the bearing hooks and supporting lugs, said side members being notched adjacent the bearing hooks to permit the assembly therewith of a member of an associated switch mechanism.
- In testimony whereof I have signed my name to this specification.

CARL ERIC ANDERSON.
